UNITED STATES PATENT OFFICE.

GEORGE SHAFFER KECK, OF PASADENA, CALIFORNIA.

EJECTING HOLDER.

Application filed April 18, 1924. Serial No. 707,336.

This invention relates to ejecting holders for materials and is designed more particularly for use with toilet materials in stick form, such as shaving soap sticks, lip sticks 5 and the like.

One object of the invention is to provide a telescopic holder having means whereby the stick of material may be advanced step by step as it is consumed at the open end of 10 the holder; and to so construct the device that the entire stick of material may be consumed without waste.

A further object of the invention is to provide such a holder which will be simple 15 in its construction, easy of operation, of a pleasing appearance and inexpensive to produce.

A further object of the invention is to provide a holder of this character with 20 means for permanently attaching the cap thereto without interfering with the placing of the cap on or removing the same from the holder.

Other objects of the invention will appear 25 as the device is described in detail.

In the accompanying drawings Fig. 1 is a side elevation of a holder embodying my invention; Fig. 2 is a vertical sectional view 30 of the same; Fig. 3 is a section taken on the line 3—3 of Fig. 2; and Fig. 4 is a section taken on the line 4—4 of Fig. 2.

In these drawings I have illustrated one embodiment of my invention and have shown the same as comprising two cylindrical sections in telescopic arrangement and provided at the opposite ends thereof with caps on which not only close the ends of the body but serve to control the ejecting of the stick. It will be understood, however, that 35 this particular embodiment has been chosen for the purpose of illustration only and that the device may take various forms without departing from the spirit of the invention.

In that form of the device here illustrated 45 the holder comprises a body portion adapted to receive one or more sticks of material. In the present instance, the body is of such a size as to receive two sticks of shaving soap arranged end to end and of a combined 50 length equal approximately to the ordinary commercial stick of shaving soap, the drawings being on an exaggerated scale. The body portion comprises a plurality of telescoping sections, and, in the present form, 55 there are two of these sections, a lower section 1 and an upper section 2, the lower end

of which extends into and is slidably mounted in the lower section 1. Preferably the sections are cylindrical in form and the upper section is of a diameter slightly larger 60 than the diameter of the stick of material which it is to receive. The lower section is of a diameter somewhat greater than the upper section in order to receive the lower portion thereof. The two sections are so connected one to the other that they may have free longitudinal movement relatively one to the other but cannot be separated. To this end the lower portion 3 of the upper section 2 is expanded to form thereon a shoulder 4, 70 the expanded portion fitting within the lower section of the holder and extending some distance beyond the shoulder to provide a suitable guide for the upper section 75 and to maintain the two sections in proper alignment. The upper edge of the lower section 1 is turned inwardly, as shown at 5, so as to overlap the shoulder 4 and form a stop to limit the outward movement of the upper section. The lower section is provided at its 80 outer end with a closure 6 which, in the present instance, is in the form of a cap screw threaded onto the lower end of the section. This cap or closure is provided with an inwardly extending part 7 adapted 85 to engage and form a support for the adjacent end of the stick of material within the holder. Preferably this inwardly extending part is formed by pressing inwardly 90 the central portion of the cap and it is spaced from the cylindrical wall of the section 1 a distance sufficient to permit the adjacent end of the upper section 2 to move between the same and the cylinder wall, thus enabling 95 the two sections to be telescoped or collapsed for substantially their full length. When 100 the stick or sticks of material have been inserted in the holder the body portion will be extended to its full length and the part 7 of the closure 6 will support the lower end of the material while the upper end thereof will project beyond the outer end of the upper section 2 a distance sufficient to expose a portion thereof for use. The outer end of the upper section is contracted or turned inwardly, as shown at 8, so that its edge will 105 engage the wall of the stick of material, hold the same firmly in position and form a tight joint between the holder and the stick of material which will prevent moisture or water from entering the holder. While the contracted portion 8 of the holder will firmly

grip the stick and may press into the same for an appreciable distance it will not materially interfere with the ejection of the stick of material. When the exposed portion of the stick has been consumed a further portion is exposed by merely pressing the two sections of the holder one toward the other so as to partially collapse the holder and thus force the stick of material lengthwise therein. The length of the inwardly extending part 7 of the closure 6 is such that when the material is in two sticks of the same initial length the upper or outer stick will be fully ejected when the holder has been completely collapsed, that is, when the two sections thereof have been telescoped to the limit of their movement. In the present instance, this movement will more than eject the upper stick and will expose for use a portion of the second stick but this is not essential to the proper operation of the device. When the upper stick has been completely used the cap or closure 6 at the lower end of the holder is removed and a further stick of material inserted therein, the holder being extended to its full length, and the cap is then replaced and the holder is ready for further use.

It is, of course, desirable to close the outer end of the holder to protect the exposed end of the stick of material and for this purpose I have provided a cap 9 which is screw threaded onto the outer end of the upper section 2 of the holder, below the inturned edge 8 thereof. This cap is of such a character and so arranged that it will also serve to limit the amount of the stick of material which can be projected beyond the end of the holder. For this purpose the end wall of the cap is spaced from the outer end of the upper section 2 a distance equal to the length of stick it is desired to expose and when it is desired to advance the stick in the holder the two sections thereof are pressed together until the stick comes in contact with the cap 9, thereby preventing further relative movement of the two sections. In order to properly position the cap with relation to the upper section the latter has been provided with a stop, such as an annular bead 10, which limits the inward movement of the cap and accurately positions the same with relation to the body portion of the holder. This bead may be formed after the two sections of the body portion have been assembled and it serves to prevent the separation of these two parts when the caps have been removed from both of them.

I have also shown the device as provided with means for permanently connecting the cap 9 with the body of the holder so as to prevent its loss, this means being of such a character that it will not interfere with the screwing of the cap on to or off of the body of the holder. For this purpose I have

loosely mounted on the section 2, between the bead 10 and the upper end of the section 1 a ring 11 which is connected by means of a chain 12 with the cap 9. Because of the flexibility of the chain and the free rotary movement of the ring the cap 9 can be readily screwed on to or off of the upper section but it cannot be detached therefrom.

The operation of the device has been fully described in connection with the description of the several parts thereof and it will be apparent that I have provided an ejecting holder for materials of this kind which is very simple in its construction, very easily operated and which is inexpensive to manufacture. Further, the device is of such a character that only a predetermined length of the stick of material can be ejected at one time and that the entire stick of material may be consumed without waste. The device is very simple of operation, it being only necessary to press the two ends of the holder one toward the other until the further movement of the stick is prevented by the upper cap. The frictional contact between the expanded portion 3 of the upper section and the inner wall of the lower section is sufficient to retain these parts in their adjusted positions. The device is preferably cylindrical in form, of a smooth harmonious construction and is of a pleasing appearance and, therefore, acceptable as a toilet article. It will further be apparent that while I have shown the holder as consisting of but two sections any desired number of sections may be employed as this would require only the duplication of the constructions here shown.

While I have shown and described one embodiment of my invention I wish it to be understood that I do not desire to be limited to the details thereof as various modifications may appear to a person skilled in the art.

Having now fully described my invention, what I claim as new and desire to secure by Letters Patent, is:

1. In a holder of the character described, a tubular body portion comprising an upper section and a lower section, one of said sections being slidably mounted within the other, and a closure for the outer end of the lower section having a part extending into said section to form a seat for the material contained within said body portion, said part being arranged to extend into the upper section when the two sections are moved one toward the other to cause the material in the lower section to be forced into the upper section.

2. In a holder of the character described, a tubular body portion comprising an upper section and a lower section, one of said sections being slidably mounted within the other, and a closure for the outer end of the

- lower section having a part extending into said section to form a seat for the material contained within said body portion, said part being spaced from the tubular wall of said 5 section to enable it to enter the upper section when said sections are moved one toward the other, said movement serving to force the material in the lower section into the upper section and to force the material in 10 the upper section out of the upper end thereof.
3. In a holder of the character described, a tubular body portion comprising a lower section and an upper section slidably mounted 15 in the lower section, a closure for the outer end of the lower section having a part extending into said section to form a seat for the material contained within said body portion, said part being arranged to extend into 20 the upper section when the two sections are moved one toward the other and to thus force the material from the upper end of said holder, and means associated with said upper section to limit the movement of said 25 material.
4. In a holder for material in stick form, a tubular body portion adapted to receive a plurality of sticks of material of equal length and arranged end to end, said body portion comprising an upper section and a 30 lower section mounted one within the other for relatively longitudinal movement, and a closure for the outer end of said lower section having a part extending into said section to engage the end of the lower stick of material and arranged to enter the upper section when said sections are moved one toward the other, said part being of such a length that when said sections are moved to 35 the limit of their movement one toward the other the lower stick of material will be forced into the upper section and substantially the entire length of the upper stick of material will be ejected from said holder.
- 40 5. In a holder for material in stick form, a tubular body portion adapted to receive a plurality of sticks of material of equal length and arranged end to end, said body portion comprising an upper section and a 45 lower section mounted one within the other
- for relatively longitudinal movement, and a closure for the outer end of said lower section having a part extending into said section to engage the end of the lower stick of material and arranged to enter the upper 55 section when said sections are moved one toward the other, said part being of such a length that when said sections are moved to the limit of their movement one toward the other the lower stick of material will be forced into the upper section and substantially 60 the entire length of the upper stick of material will be ejected from said holder, and a closure for the outer end of said upper section having a part spaced from the 65 end of said upper section to permit a predetermined portion only of said stick to be ejected at one time.
6. A holder of the character described, comprising two cylindrical sections slidably mounted one within the other, that portion of the inner section which lies within the outer section being expanded to provide a shoulder and the adjacent end of the outer shoulder being turned inwardly into the 70 path of said shoulder, a closure for the end of the outer section having a part extending into said section to engage the material therein and arranged to enter the upper section when said sections are moved one toward the other, and a closure for the outer end of the inner section having means to limit the movement of the material when said sections are moved one toward the other.
7. A holder of the character described, comprising two cylindrical sections slidably mounted one within the other, a closure for the outer end of one of said sections having a part extending into said section to support the material within said holder, said part being arranged to enter the other section when said sections are moved one toward the other, and a removable closure for the outer end of said other section having a part arranged in line therewith to limit the movement of material beyond the end of the last mentioned section.
- In testimony whereof, I affix my signature hereto.

GEORGE SHAFFER KECK.
